UNITED STATES PATENT OFFICE.

AMBROSE S. RAY, OF BELLEFONTE, PENNSYLVANIA.

BOX.

No. 878,896.

Specification of Letters Patent.

Patented Feb. 11, 1908.

Application filed July 19, 1907. Serial No. 384,597.

To all whom it may concern:

Be it known that I, AMBROSE S. RAY, a citizen of the United States, residing at Bellefonte, in the county of Center and State of Pennsylvania, have invented certain new and useful Improvements in Boxes; and I do hereby declare the following to be a full, clear, and exact description of the invention, such as will enable others skilled in the art 10 to which it appertains to make and use the same.

My invention relates to new and useful improvements in boxes, and more particularly to that class adapted to be employed 15 for shipping various articles, such as eggs, fruits, and the like, and my object is to provide means for holding the parts of the box together and in a compact form for re-shipment purposes.

20 A further object is to provide means for holding the parts of the box rigid when in its assembled position.

Other objects and advantages will be hereinafter referred to and more particularly 25 pointed out in the claims.

In the accompanying drawings which are made a part of this application, Figure 1 is a perspective view of the box complete in its assembled position. Fig. 2 is a transverse, sectional view thereof. Fig. 3 is a perspective view of the box in its folded or knocked-down position. Fig. 4 is a transverse, sectional view of the box when in its folded position. Fig. 5 is a detail perspective view of a locking clip. Fig. 6 is a detail, sectional view showing the manner of securing the side and end walls to the bottom of the box, and, Fig. 7 is a detail, perspective view of one upper corner of the box.

40 Referring to the drawings in which similar reference numerals designate corresponding parts throughout the several views, 1 indicates the base or floor of the box, around the edges of which are disposed flanges 2, 45 said flanges extending upwardly from the base to form a receptacle for the side and end walls 3 and 4, respectively, when the walls are folded together.

The lower edges of the side and end walls 50 are provided with bars 5 and 6, respectively, around which are disposed straps 7 and 8, respectively, carried at the upper ends of bolts 9 and 10, respectively, said bolts being directed through the base 1 and secured 55 thereon in any preferred manner, as by means of nuts 11, said bolts forming hinges

for the side and end walls, that portion of the bars 5 and 6 engaged by the straps 7 and 8 being reduced and made circular to provide spindles, around which the straps extend and by which means the side and end walls are permitted to swing.

The bolts 9 are longer than the bolts 10, so that the side walls may be folded inwardly over the end walls, said bolts 9 being of sufficient height to allow the bars 5 to extend over the end flanges 2 for a purpose to be hereinafter set forth.

The upper edges of the end walls 3 and 4 are reinforced by means of cleats 12 and 13, respectively, and said walls are held in their vertical positions by pivotally mounting on the inner faces of the side walls 3, L-shaped latches 14, the free end of each latch being at right angles to the face of the side wall and 75 provided with a notch 15, which is adapted to engage a headed pin 16 on the end walls, so that when the side and end walls are elevated and the latch engaged with the pin 16, the walls will be firmly held in their vertical 80 positions.

The box is provided with a cover 17, which is arranged to fit snugly between the upper edges of the side walls 3 and 4 and is held in position between the upper edges of 85 the walls by securing strips 18 across the upper surface of the cover, said strips being of sufficient length to extend beyond the edges of the cover and engage the upper edges of the side walls and the cleats 12, thereby preventing the cover from descending between 90 the side and end walls.

The cover 17 is held in operative relation with the side and end walls by means of clips 19, which are provided at one end with 95 a pocket 20 and at the opposite end with an extension 21, the pocket being adapted to engage and fit over the meeting ends of the cleats 12 and 13, while the extension 21 is provided with an elongated slot 22, through 100 which extends a bolt 23, carried by the cover 17, the upper end of said bolt being threaded to receive a wing nut 24, by which means the clips are firmly clamped in position over the cleats and as best shown in Fig. 1 of the 105 drawing, when the clips are properly placed over the ends of the cleats, the cover will be held against casual removal from the box and the side and end walls at the same time additionally reinforced. These clips are 110 also employed for holding the parts of the box in its folded position and for securing

the cover thereover, said clips, when the box is in its folded position, engaging the extended ends of the bars 5, as best shown in Fig. 3 of the drawings, thereby positively holding the side and end walls in their folded position and the cover over said folded parts, the strips 18, in this instance, resting upon the bars 5.

In folding the box herein shown, the wing nuts 24 are first loosened, after which the clips 19 are moved endwise until the pocket 20 is free of the cleats 12 and 13, when the cover 17 is removed. The latches 14 are then swung upwardly until the notches 15 are released from the pin 16 when the end walls 4 are folded inwardly, as best shown in Fig. 4 of the drawings. The two side walls 3 are then folded inwardly and downwardly over the two end walls, the width of the box 20 being preferably twice the width of the height of the side walls, so that when said side walls are folded inwardly, the upper edges thereof will abut against each other, while the height of the bolts 9 above the bolts 10 is such that the laterally extended portions of the latches 14 will engage the end walls and hold the side walls in a horizontal position when the parts of the box are folded together. After the side and end 25 walls are thus folded, the cover 17 is placed over the folded parts and the bars 5, when the clips 19 are again moved inwardly and the pockets 20 engaged with the extended ends of the bars 5, when by again tightening 30 the wing nuts 24, the parts of the box will be securely held in their folded position.

It will thus be seen that I have provided a very cheap and economical form of folding box and one wherein the walls will be rigidly held in their assembled or folded position and the cover securely fixed thereover. It will further be seen that the box may be folded to occupy a minimum amount of space when it is desired to re-shape the same, and that 45 the box as constructed is strong and durable in all its parts.

What I claim is:

1. In a box of the class described, the combination with a base; of side and end walls 50 for said base, bars at the lower edge of said

side and end walls, the bars at the lower edge of the side walls extending beyond the ends thereof, means extending between said base and bars to pivotally secure said walls to the base, cleats at the upper ends of said walls, 55 a cover for said box, clips carried by said cover, having an elongated slot at one end and a pocket at the opposite end, bolts carried by said cover, and extending through said slots and means to adjustably secure 60 said pockets over the ends of said cleats, when the box is in its assembled position and over the projecting ends of the bars on the side walls when the box is in its folded position, whereby the parts of the box will be 65 held in their assembled or folded positions.

2. In a box of the class described, the combination with a base, having a flange around the edges thereof; of side and end walls for said base, bars at the lower edges of said side 70 and end walls, bolts fixed to said base, straps at the upper ends of said bolts adapted to engage the bars on the side and end walls and hingedly secure the same to the base, cleats at the upper edges of said side and end walls, 75 a cover adapted to fit between the upper edges of said walls and means carried by said cover adapted to engage said cleats and lock the cover in position over the box.

3. In a box of the class described, the combination with a base, side and end walls pivotally secured to said base, and cleats at the upper edges of said side and end walls; of a cover for said box, clips on said cover adapted to extend over said walls and cleats, 85 pockets at one end of said clips adapted to engage the ends of said cleats, the opposite ends of said clips having elongated slots, bolts extending through said slots and means on the bolts to lock said clips in their adjusted position, whereby the cover will be firmly held in engagement with said walls and the walls reinforced.

In testimony whereof I have signed my name to this specification in the presence of 95 two subscribing witnesses.

AMBROSE S. RAY.
